US0D1050179S

(12) **United States Design Patent** (10) **Patent No.:** **US D1,050,179 S**
(45) **Date of Patent:** **** Nov. 5, 2024**

(54) **DISPLAY PANEL OR PORTION THEREOF
WITH GRAPHICAL USER INTERFACE**

(71) Applicant: **NCSOFT Corporation**, Seoul (KR)

(72) Inventors: **Kwang Han Kim**, Seongnam-si (KR);
Mi Hye Yu, Seongnam-si (KR); **Ji Young Kim**, Seongnam-si (KR);
Byeong Hoon Lee, Seongnam-si (KR)

(73) Assignee: **NCSOFT Corporation**, Seoul (KR)

(**) Term: **15 Years**

(21) Appl. No.: **29/857,449**

(22) Filed: **Oct. 21, 2022**

(30) **Foreign Application Priority Data**

Jun. 9, 2022 (KR) 30-2022-0022934

(51) **LOC (14) Cl.** **14-04**

(52) **U.S. Cl.**

(57) **CLAIM**

The ornamental design for a display panel or portion thereof with graphical user interface, as shown and described.

DESCRIPTION

The FIGURE is a front view of a display panel or portion thereof with a graphical user interface, showing our design. The broken lines depict the display panel and form no part of the claimed design. Any grayscale shading shown likewise illustrates a contrast in appearance and forms no part of the claimed design.
